MECHANICAL PENCIL WITH SCREW FEED
AND HOPPER TYPE MAGAZINEBlanchard D. Smith, Atlanta, Ga., assignor to
Scripto, Inc., Atlanta, Ga., a corporation of
Georgia

Application October 18, 1946, Serial No. 704,098

19 Claims. (Cl. 120—18)

1

This invention relates to mechanical pencils with a screw feed and hopper type magazine.

In pencils where the leads are forcibly fed through the tip which frictionally engages the lead as it emerges, the pencil is generally constructed so that it is necessary to remove the tip when a new lead is inserted. This feature is obviously objectionable.

The primary object of this invention is the provision of an improved pencil wherein the leads are fed toward and through the point.

Another object of the invention is the provision of an improved pencil which has a magazine and will feed out a new lead without removing any part of the pencil.

Another object of the invention is the provision of an improved feeding mechanism for a pencil having a minimum number of parts.

Still another object of the invention is the provision of an improved pencil wherein when a new lead is necessary, it is only necessary to back up the driving element with the pencil in a vertical position and the point down and then force the driving nut downwardly to force a new lead into the lead tube and into position for writing.

A further object of the invention is the provision of a pencil having a feeding mechanism which, while the parts when assembled will be held firmly in place, may be taken apart without difficulty.

A still further object of the invention is the provision of a magazine mechanical pencil having a lead-propelling member with mechanism for moving the lead driving means from operative position at the end of the upper position and for movement to operative position when the reverse movement moves the nut downwardly toward the pencil point.

Other and further objects will be apparent from a reading of the complete specification.

Referring to the drawings wherein is illustrated an embodiment of the invention:

Fig. 1 is a vertical section of a pencil showing an embodiment of the invention.

Fig. 2 is a sectional view on the line 2—2 of Fig. 1.

Fig. 3 is a sectional view on the line 3—3 of Fig. 1.

Fig. 4 is a sectional view on the line 4—4 of Fig. 1.

Fig. 5 is a detail sectional view taken adjacent the throat of the lead receiving tube, showing the propeller in its retracted position.

Fig. 6 is a detail sectional view similar to Fig. 5 but showing the propeller in its driving posi-

2

tion forcing the lead downwardly toward the pencil point.

Fig. 7 is a detail perspective view of the propeller.

Fig. 8 is a cross sectional view taken on the line 8—8 of Fig. 1.

Similar reference characters refer to the same or similar parts throughout the specification and drawing.

10 The working parts of the pencil which here illustrate the invention, are three in number: the barrel, the lead-carrying tube and the propeller, the relatively rotary movement of the barrel and lead-carrying tube causing the propeller to move toward or from the point, according to the relative direction of the barrel and lead-carrying tube. The details of the construction of these parts and their coactive relation to each other will now be described.

20 The barrel comprises a magazine chamber 20a at its upper end, in which are carried the leads 21. At the lower end of the magazine chamber 20, is a conical face 20b which serves to guide the leads to a position where they can be fed to an operative position as will be later described.

25 Below the conical face 20b is a substantially cylindrical short chamber 20c which has at its bottom, a very short preferably conical shoulder 20d to assist in the assembling and disassembling operations to be later described. Below the shoulder 20d is a cylindrical passage which is threaded for the greater portion of its length as at 20g but is not threaded for the remainder as at 20h, for a purpose which will later appear.

30 35 The lower end of the barrel 20 is provided with a flat surface 20f, for cooperation with the lead-carrying tube which will now be described.

The lead-carrying tube, which I have designated generally by the reference character 22 has at its lower end a point section 22a which is tapered and ends in a split portion having a split 40 45 50 55 22b which enables the sides of the tube 22 at the point to grip the lead, as will later appear. At the top of the point section 22a is a flat surface 22c which is coextensive with the surface 20f, the outer surfaces of the barrel 20 and the point section 22a forming a smooth tapered surface.

Above the point section 22a of the lead-carrying tube 22 is a cylindrical section 22d of a size 50 55 to fit the inner diameter of the threaded portion 20g and the unthreaded portion 20h. For a portion of the length of the lead-carrying tube 22 and at the top, is a narrow slot 22e which provides two resilient end sections 22f, as illustrated

in Figs. 3 and 8. The purpose of this slot 22e will later be described.

At the top of the lead-carrying tube 22 is a slightly enlarged cylindrical portion 22g of a size to fit the short cylindrical opening or passage 23c of the barrel 20. Extending from the surface 22c to the upper end of the lead-carrying tube 22 is a slot 22g which at its upper end is half on one side of the slot 22e and half on the other side. The cross-section of the slot 22g is of T-shape, the cross of the T being adjacent the outer periphery of the cross-section and the upright portion of the T being at and connecting to the tube or bore 22h which is of a size to receive the lead for which the pencil is designed. The lower end of the tube or bore 22h is at the point of the pencil and extends the axial length of the lead-carrying tube 22.

After the formation of the two points 22j, by the slot 22b and the tube or bore 22h, during manufacture, the points 22j are pressed toward each other slightly in order to slightly lessen the diameter of the bore 22h.

The propeller will now be described. This propeller which has been designated generally by the reference character 23 is provided with a threaded portion 23a which engages with the threaded portion 20g of the barrel 20. Upwardly extending from the threaded portion 23a is a tapered shank 23b which is integral with a cam head 23c. The cam head 23c has a width slightly less than the width of the slot or groove 22g and is for travel therein. The cross-section of the outer portion of the cam head is of wedge shape as at 23d in order that when the propeller is backed up, it may find its way between the leads which are carried in the magazine chamber 20a. The purpose of this latter feature is to clear the throat or opening at the upper end of the tube or bore 22h to permit a sure entry of the leads 21 therein during the reloading operation as will be later described.

The propeller 23 is provided with a rib 23e extending from near one of its ends to near the other end. At one end and extending from the cam head 23c is the lead driving lip or finger 23f. This lip extends toward the axis of the pencil a sufficient distance to engage the end of the lead and to propel the lead toward the point when it is desired to feed lead downwardly. At the threaded end of the propeller, there is an extension of the rib 23e. This extension, I have designated by the reference character 23g. This latter, it will be noted from Fig. 7, is at an angle to the rib 23e in order to permit the cam head to swing outwardly during the reloading operation. The lower thread 23h of the driving nut 23, in conjunction with the shoulder 23j which acts as a fulcrum, operates to force the cam head 23c outwardly when the latter reaches the magazine chamber 20a. It is to be understood that the ribs 23e, 23g and the driving lip or finger 23f are all of a width that may slide axially in the inner part of the slot 22g, the lip or finger 23f being long enough to extend into the bore or tube 22h.

The barrel member 20 has an opening at the top in which is provided a split sleeve 24 which is integral with a clip 25 and nearly surrounds an eraser 26. The eraser is held in place by projecting portions 24a of the split sleeve 24. As the eraser wears down, the sleeve may be removed and the eraser pulled out to expose more of its length for future use. These parts incident to the eraser are old in the art and are not a part of the invention per se, as claimed herein.

Having described the parts in detail, their assembly and operation will now be described.

When it is desired to assemble the working parts of this invention, the upper end of the lead-carrying member 22 is inserted at the bottom of the barrel member 20. This is facilitated by pressing together the ends 22j. After the upper end of the lead-carrying member 22 is started and is within the lower end of the barrel member 20, the driving element or propeller 23 is inserted in the groove 22g with the rib 23e in that portion of the groove next to the bore 22h. When in this position, the lead-carrying member 22 may be turned as the propelling element 23 is threaded into the threaded portion 20g of the barrel 20. As the propelling element 23 passes the surface 20f, the lead-carrying member 22 may be pushed directly up into the barrel 20. Just before the lead-carrying member 22 reaches its operative position, the enlarged portion 22g enters the chamber 20a and when it is in place, the resilience of the two split portions 22j causes them to snap into place to hold the parts 20 and 22 in proper relation for operation. If it should be necessary to separate the parts, this can be done, if the shoulder 20d is not too pronounced, by pulling the point out in a direction opposite from the direction of the movement during its assembling operation.

It is to be understood that in the preparation of the member 22 for use, the split members 22j are squeezed toward each other sufficiently so that when released, the split portions will be close enough together that they will grip the lead when it comes into contact with the two portions of the point.

If the barrel 22 is now held while the lead-carrying member 22 is turned to back the lead-driving element 23 to its upper position, there will be a time when the upper extension of the element 23, will reach the magazine chamber 20a. When the upper cam head 23c reaches the point where the cam face 23k rides over the edge of the conical face 20b, the cam head will move outwardly.

When the assembly of the parts 20, 22 and 23, takes place, the propeller lip 23f enters the bore 22h. And when the cam head 23c enters the magazine chamber 20a, moves outwardly, the lip 23f will be withdrawn from the bore 22h. This leaves the bore 22h unobstructed. If there are writing leads in the magazine chamber 20a, the wedge shape portions 23d of the cam head 23c will work its point between the leads 21, as the relative turning between the cam head 23c and the barrel 20 takes place. As the cam head 23c is fully clear of the leads 21 and the lower end of the magazine chamber 20a, it is clear from Fig. 5 that the lip 23f is out of line with the bore 22h.

The operation of the several parts which cause this outward movement of the cam head 23c will now be described.

The placing of the teeth of the threaded portion 23a is such that when the propeller 23 is moved upwardly toward the magazine, an inwardly radial force will be exerted on the threaded portion. Counteracting this force is the force exerted between the fulcrum 23j and the wall of the groove 22g. The lines of the resultants of these two forces are spaced apart, the force of the fulcrum being exerted between, and opposite to, the resultant force of the threaded portion 23a and the contact point of

the cam head 23c with the threaded portion of the barrel.

After the wedge shape portion 23d of the cam head 23c has cleared the leads 24 and has reached its outer position as illustrated in Fig. 5, and with the pencil in its vertical position with the point down, one of the leads in the magazine chamber will ride down on the conical surfaces 20b and 22j and will enter the upper end of the bore 22h and drop to a position below the lower end of the lip 23f. If now the propeller 23 is moved downwardly by relative turning of the barrel 20 and the lead carrying tube 22, the came face 23k rides inwardly on the edge of the conical face 20b. This brings the lip 23f into the bore 22h and in a position to drive the lead 24 downwardly toward the point of the pencil. This action forces the lead at the bottom of the point out where it is ready for use.

If it is desired to fill the bore with lead and the driving element has not reached the lowest position, it is obvious that another writing lead could not go down in the bore for the full distance so that the lip 23f could get above its end. In this case, the lip 23f will simply break off the lead just above the top of the bore 22h and then the lip 23f will pass above the new end caused by the break and the pencil is in operation.

As already described, the upper portion of the inside of the bore 22h is not threaded. The threads extend to the point where the cam head 23c will be permitted to reach the outer position shown in Fig. 5 and will then be stopped by the end of the thread. This construction is important to prevent the screwing of the driving element up too far or perhaps out of the top into the lead magazine chamber 20a.

While I have described and illustrated an embodiment of the invention in detail, it is to be understood that the disclosure is merely illustrative and that modifications and changes may be made without departing from the spirit of the invention and within its scope as claimed.

Having described the invention, what is claimed is:

1. A pencil having a magazine chamber comprising a barrel member, a member rotatable relatively thereto, a lead-propelling element, thread and slot means coactive between the driving element and the two members to hold the propelling element to a helical movement relative to one of the members and to longitudinal movement relative to the other, and coacting means to remove the lead-propelling element from its lead-propelling position beyond a predetermined point and into the magazine when moving in one direction and for restoring it to its lead-propelling position at a predetermined point and while in the magazine chamber when moving in the opposite direction.

2. A pencil having a magazine chamber comprising a barrel member, a member rotatable relatively thereto, a lead-propelling element having a lead-contacting lip, thread and slot means coactive between the propelling element and the other two members to hold the propelling element to a helical movement relative to one of the members and to longitudinal movement relative to the other, and coacting means including a cam to remove the lead-contacting lip from contact with the lead in its lead-propelling position when moving in one direction into the magazine chamber and for restoring it to lead-propelling position when moving in the opposite direction.

3. A pencil having a magazine chamber comprising a barrel member, a member rotatable relatively thereto, a movable lead-propelling element having a lead-contacting lip spaced from the main body of the propelling element and pivotal about the operative position of the main body of the propelling element and thread and slot means coacting with the propelling element to move the lead contacting lip out of its lead-propelling position when moving in one direction into the magazine chamber and for bringing it into propelling contacting position when moving in the other direction as it leaves the magazine chamber.

15 4. A pencil having a magazine chamber comprising a barrel member, a member rotatable relatively thereto, a movable lead-propelling element having a lead-contacting and propelling lip movable into the magazine chamber near one end of its movement, means for moving the lip away from the lead propelling position and means on the propelling element to move the leads in the magazine to one side when the lip is moved from its propelling position.

25 5. A pencil having a magazine chamber comprising a barrel member, a member rotatable relatively thereto, a propelling element having a lead-contacting and propelling lip movable into the magazine chamber near one end of its movement, means for moving the lip away from the lead-propelling position and a wedge-shaped member for passing between the leads in the magazine chamber to provide space for the lip to move from its lead propelling position to allow a new lead to move to a position to be engaged by the propelling lip.

6. A pencil having a magazine chamber comprising a barrel member, a member rotatable relatively thereto, a propelling element, means coactive between the two members to hold the propelling element to a helical movement relative to one of the members and to longitudinal movement relative to the other member, one of the members having a threaded portion, and the other having a longitudinal slot, the propelling element having a threaded portion for movement by the threaded portion of the member and having a portion slidable in the slot, the propelling element having an extension with a lead propelling lip which is movable into and from the magazine chamber and a means for coacting with the slot for swinging the lip away from its propelling position when it enters the magazine chamber.

55 7. A pencil having a magazine chamber comprising a barrel member, a member rotatable relatively thereto, a propelling element, means coactive between the two members to hold the propelling element to a helical movement relative to one of the members and to longitudinal movement relative to the other, one of the members having a longitudinal slot, the propelling member having a part coacting with the slot and movable therein and having an extension with a swinging lead-propelling lip movable into and from the magazine chamber portion on the lead-propelling lip to move the leads in the magazine chamber to one side and provided with a cam for moving the lip into propelling position.

60 8. A pencil having a magazine chamber comprising a barrel member having a threaded portion near its point end, a tubular member having a lead bore to receive the writing lead, and of a size to fit the interior of the barrel member, the 65 tubular member having a longitudinal slot for a

guide at its periphery, a longitudinally movable propelling element within the slot and having a thread-coacting means for coaction with the threads of the barrel member, and having a cam head provided with a lead-propelling lip, movable into and from the magazine chamber, the propelling element having a pivotal fulcrum between the thread-coacting means and head, the thread-coacting means and the slot constituting a swinging means for moving the lead-propelling lip away from its operative position when it is in the backed-up position, to clear the path of an incoming lead into the bore when the lead-propelling lip is in the magazine chamber.

9. A pencil having a magazine chamber comprising a barrel member having a threaded portion near its point end, a tubular member having a lead bore to receive the writing lead and of a size to fit the interior of the barrel member, the tubular member having a longitudinal slot for a guide at its periphery, a longitudinally movable propelling element within the slot and having a thread-coacting means for coaction with the threads of the barrel member, and having a cam head provided with a lead-propelling lip, movable into and from the magazine chamber, the propelling element having a pivotal fulcrum between the thread-coacting means and head, the thread-coacting means and the slot constituting a swinging means for moving the lead-propelling lip away from its operative position when it is in the backed-up position, to clear the path of an incoming lead into the bore when the lead-propelling lip is in the magazine chamber, and a cam connected with the lead-propelling lip coacting with the bottom of the magazine chamber to forcibly cause the lead-propelling lip to return to a position above the bore where upon further movement it will operate to move the lead downwardly in the bore.

10. A pencil comprising a barrel member having a threaded portion near its point end and a magazine chamber thereabove, a tubular member, having a lead-bore to receive the writing lead, and extending within the barrel member from its point end thereof substantially to the magazine chamber, the tubular member having a longitudinal slot at its periphery extending to the bore, the magazine chamber having a conical surface at its bottom for directing the leads to the bore, the pencil having a gripping slit at its point for gripping the writing end of the lead, a longitudinally movable propelling element in the slot and having a thread means for engaging cooperatively with the threaded portion of the barrel, the propelling element having a cam head provided with a lead-driving lip radially spaced from the threaded means and a cam face for engaging the conical surface to guide the propelling lip to and from its propelling position and a fulcrum means between the threaded means head about which the propelling lip swings to move to and from its operative position.

11. A pencil comprising a barrel member having a threaded portion near its point end and a magazine chamber thereabove, a tubular member, having a lead-bore to receive the writing lead, and extending within the barrel member from its point end thereof substantially to the magazine chamber, the tubular member having a longitudinal slot at its periphery extending to the bore, and having a slotted upper end and a shoulder to engage a similarly shaped recess in the barrel member, to hold the tubular member and barrel members together, the magazine

chamber having a conical surface at its bottom for directing the leads to the bore, the pencil having a gripping slit at its point for gripping the writing end of the lead, a longitudinally movable propelling element in the slot and having a thread means for engaging cooperatively with the threaded portion of the barrel, the propelling element having a cam head provided with a lead-propelling lip spaced from the threaded means and a cam face for engaging the conical surface to guide the propelling lip radially to and from its propelling position and a fulcrum means between the threaded means head about which the propelling lip swings to move to and from its operative position.

12. A pencil comprising a barrel member having a threaded portion near its point end and a magazine thereabove, a tubular member having a lead-bore to receive the writing lead and extending within the barrel member from its point end substantially to the magazine chamber, the tubular member having a longitudinal slot at its periphery extending to the bore, and having a slotted upper end and a shoulder to engage a similarly shaped recess in the barrel member to hold the tubular member and barrel members together, the magazine chamber having a conical guiding surface at its bottom for directing the leads to the bore, the pencil having a gripping slit at its point for gripping the writing end of the lead, a longitudinally movable propelling element in the slot and having a thread means at one end for engaging cooperatively with the threaded portion of the barrel, the propelling element having a tapered extension and a propelling lip on the tapered extension spaced from the threaded means and having a cam face for engaging the conical surface to guide the propelling lip radially to and from propelling position in the lead bore and also having a wedge shape portion on the opposite side from the lip to move the leads in the magazine chamber to one side and a fulcrum means intermediate the ends of the propelling element about which the propelling lip swings to move it to and from its operative position.

13. A pencil having a magazine chamber and a lead feeding mechanism, including a lead bore and a lead propelling lever having a lead-end engaging means and means within the body of the pencil for moving the propelling lever about its fulcrum to an inoperative position when the propelling means is backed up and for returning it to propelling position when the propelling means is fed downwardly.

14. A pencil having a magazine chamber and a lead-feeding mechanism, including a lead propelling lever having a lead-end engaging means and means within the pencil body for moving the propelling lever about its fulcrum to a position where its propelling part is in the bore when at one position and for moving the propelling part from the bore when in another position.

15. A pencil having a magazine chamber and a lead feeding mechanism, an outer barrel member having a recess and an inner member, the inner member having a lead-bore through its length, a writing point at one end and an expanding member at its other end for registration with and to snap into and be held by the wall of the recess.

16. A pencil having a magazine chamber and a lead-feeding mechanism, the lead-feeding mechanism including a fulcrumed lead-propel-

ling lever, a lip on the element for contacting and moving the lead and means for pivoting the lever to move the lip into or out of the path of the end of the lead.

17. A pencil having a magazine chamber and a lead-feeding mechanism, the lead-feeding mechanism including a lead-propelling lever, a lip on the element for contacting and moving the lead and means for moving the lever about its fulcrum to move the lip into or out of the path of the end of the lead.

18. A pencil having a magazine chamber and a lead-feeding mechanism including coacting threaded means, a lead-propelling element, a lip on the element for contacting and moving the lead, one of the threads extending from the axis of the body member farther than the other threads.

19. A pencil having a magazine chamber and a lead-feeding mechanism including a helical thread, a lead-propelling element having coacting element having coacting threads, the line of

threads being out of parallelism with the axis of the propelling element as a whole, thus normally tending to pivot the lead-driving element and means for restraining the pivotal movement during a part of the lead movement and for permitting pivotal action as the element approaches the magazine chamber.
